UNITED STATES PATENT OFFICE.

TIMOTHY W. GETMAN, OF WEST TROY, NEW YORK.

MACHINE FOR TRIMMING SOFT-METAL LININGS OF CAR-AXLE BEARINGS.

SPECIFICATION forming part of Letters Patent No. 396,652, dated January 22, 1889.

Application filed August 13, 1888. Serial No. 282,684. (No model.)

To all whom it may concern:

Be it known that I, TIMOTHY W. GETMAN, a citizen of the United States, residing in the village of West Troy, in the county of Albany and State of New York, have invented certain new and useful Improvements in Machines for Trimming Soft-Metal Linings of Car-Axle Bearings, of which the following is a specification, reference being had to the accompanying drawings.

My invention relates to machines for trimming to a curve or bevel the end parts of the thin soft-metal linings of car-axle bearings, and especially to such machines as hold the car-axle bearing upon a stationary bed, and in which the trimming is accomplished by the use of a hand-lever carrying a trimming-blade and having a universal joint at its fulcrum end.

The primary objects of my invention are to provide superior means for clamping and holding the car-axle bearings upon the stationary bed, for readily clamping and holding on the bed car-axle bearings of different lengths, and for presenting the same for the action of the trimming device. I attain these objects by the mechanism illustrated in the aforesaid drawings, in which—

Figure 1 is a perspective view of the mechanism as when clamping and holding a car-axle bearing for the action of the trimming-lever. Fig. 2 is a plan of the same mechanism as it appears when open to release or to receive a car-axle bearing, which is indicated in this figure by dotted lines, the trimming-lever being turned to one side and mostly broken off. Fig. 3 is a partial elevation and longitudinal section of the same at the line $z z$ in Fig. 2, as when clamping and holding for the action of the trimming-lever a car-axle bearing, which is represented in this figure in longitudinal section by broken lines. Fig. 4 is an isometrical representation of the bed-plate of the mechanism. Fig. 5 is an isometrical drawing of the cam-lever which operates the clamps, of which isometrical representations are presented by Figs. 6, 7, and 8. Fig. 9 is an isometrical illustration of the movable stop at the forward end of the car-axle bearing in Figs. 1 and 3. Fig. 10 shows in plan a modification of the cam-lever, and Fig. 11 indicates the manner of

its connection with correspondingly-modified clamps.

Like letters refer to similar parts in the several figures.

The bed-plate A is securely mounted upon supports B on a base, B', so as to leave an open space immediately under and around that portion of the bed-plate upon which the car-axle bearing Y is held for the action of the trimming-lever C, which has the two-edged trimming or shaving blade c.

The bed-plate has separated seats a a and recesses b b' b², so that the back of the car-axle bearing may rest firmly on said seats, whichever end of the axle-bearing is placed to the front to be acted on by the trimmer.

The bed-plate is furnished with an end stop, as D or D', for one end of the car-axle bearing to rest against, as indicated in Figs. 1 and 3, and has, as shown in Fig. 4, a lengthwise-slotted way, E, and two transverse slotted ways, F F', in which fit, respectively, the sliding end clamp, G, Fig. 6, and the sliding side clamps, H H', Figs. 7 and 8, which have webs d extending downward through the slotted ways, and top flanges, e, above and bottom flanges, f, below said ways, whereby the clamps are so engaged with the ways, as in Figs. 1, 2, and 3, that the clamp cannot be displaced thereon nor detached therefrom except by sliding the clamps in the lengthwise direction of their respective ways.

To provide cheap, effectual, and durable means for easily and simultaneously sliding the clamps G H H' either outward or inward along the slotted ways, and thereby securely clamping and holding fast upon the bed-plate a suitable car-axle bearing, Y, or releasing the same, the hand-lever I is mounted under the bed-plate upon a suitable pivot-support, as at J, Fig. 3, so as to be freely turned to and fro thereon by hand in a plane parallel or nearly parallel to the top face of the bed-plate. The lever I also has a cam, as g, which fits in a transverse slot, h, Fig. 6, in the lower part of the end clamp, G, as in Fig. 3, and the lever has cams g' g², which likewise work in transverse slots h' h² in the lower parts of the clamps H H', respectively. The cams of the lever I are so arranged and engaged with the clamps that by turning the lever in one direction, as indicated by the arrow y in Fig.

2, all the clamps will be simultaneously slid inward, so as to securely clamp and hold the car-axle bearing endwise between the end stop D or D' and the end clamp, G, and sidewise 5 between the side clamps, H H', and that by turning the lever I in the opposite direction all the clamps will be simultaneously slid outward to release the car-axle bearing and receive another one.

10 As an equivalent for the raised cams on the lever I and the transverse slots in the lower parts of the clamps, the lever may have the cams in the form of slots, as shown in plan in Fig. 10 at g³ g⁴ g⁵, and the clamps each have a 15 downwardly-extending lug, as illustrated in side elevation at h³ in Fig. 11, to engage with the slot-cams of the lever, as shown in the latter figure.

To provide means for readily clamping 20 upon the bed-plate car-axle bearings of two decidedly different lengths, the bed-plate has the permanently-fixed end stop D, and adjacent thereto has the vertical sockets i i, Fig. 4, in which the movable end stop, D', Fig. 9, 25 fits in Figs. 1, 2, and 3, and is engaged with a lever, j, which is pivoted at j' to the bed-plate, and by which lever the movable stop can be extended above the face of the bed-plate, as shown by full lines in Figs. 1 and 3, 30 so as to serve as the stop for the forward end of the shorter car-axle bearings, and can be depressed even with or below the face of the bed-plate, so that the fixed stop D shall serve as the stop for the forward end of the longer 35 axle-bearings.

By having in or through the heads of the clamps set-screws, as k in Fig. 12, the clamps can be used, in connection with the stop D or D', to clamp and hold fast on the bed-plate 40 car-axle boxes of many variously different length and widths.

L is a stock which is mounted on a fixed support, M, upon and extending above the rear portion of the bed-plate, and has at its 45 forward end a socket, in which works the fulcrum-ball l of the trimming-lever. The stock L is adjustable along a guideway, m, on the support M in the lengthwise direction of the bed-plate by screw-bolts n, extending through 50 parts of said support and through slots o in the stock, to thereby adjust the trimming-lever C with its blade c in proper position in respect to the forward end of

whatever car-axle bearing shall be held on the bed-plate, and at various inclinations to the 55 central lengthwise line, x x, Fig. 3, in the face of the car-axle bearing.

The trimming-lever C has handles c', which are grasped by the hands of the person using the trimmer, and thereby moved to and fro— 60 about and with the ball l as a universal fulcrum—in the proper curved courses, and with suitable varying downward and lateral pressure to cause the blade c to properly shave or trim off the superfluous end portion of the 65 soft-metal lining of the car-axle bearing clamped upon the bed-plate.

I claim as my invention—

1. The bed-plate furnished with an end stop for a car-axle bearing and having the 70 lengthwise and transverse slotted ways, combined with the sliding clamps extending through and engaging with said slotted ways, and the operating-lever mounted under the bed-plate and having cams engaging with 75 said clamps, substantially as described.

2. The bed-plate having the lengthwise and transverse slotted ways, the fixed end stop, D, and the vertical sockets i, adjacent to said stop, the movable end stop, D', fitting in said 80 sockets, and the lever j, pivoted to the bed-plate and engaging with said movable stop, combined with the sliding clamps upon, extending through, and engaging with said slotted ways, and the lever mounted under 85 the bed-plate and having cams engaging with said clamps, substantially as set forth.

3. The combination, with the bed-plate furnished with an end stop for a car-axle bearing and having the lengthwise and transverse 90 slotted ways, the sliding clamps upon, extending through, and engaging with said slotted ways, and the lever mounted under the bed-plate and having cams engaging with said clamps, of the stock L, mounted upon and 95 adjustable lengthwise along and above said bed-plate, and the hand-lever C, having the trimming-blade and connected to said stock by a ball-and-socket joint, as set forth.

In testimony whereof I hereunto set my 100 hand, in the presence of two subscribing witnesses, this 4th day of August, 1888.

TIMOTHY W. GETMAN.
